FIG. 2 is front, left perspective view of the design of FIG.
1;

FIG. 3 is a left perspective view from below of the design
of FIG. 1;

FIG. 4 is a rear, left perspective view of the design of FIG.
1;

FIG. 5 is a rear perspective view from below of the design
of FIG. 1;

FIG. 6 is a front view of the design of FIG. 1;

FIG. 7 is a rear view of the design of FIG. 1;

FIG. 8 is a right side view of the design of FIG. 1;

FIG. 9 is a left side view of the design of FIG. 1;

FIG. 10 is a top view of the design of FIG. 1;

FIG. 11 is a bottom view of the design of FIG. 1;

FIG. 12 is a cross-sectional view of the design of FIG. 1
taken along line 12-12 in FIG. 11;

FIG. 13 is a front, top perspective view of the hammer of
FIG. 1, but illustrated without surface shading;

FIG. 14 is front, left perspective view of the design of FIG.
13;

FIG. 15 is a left perspective view from below of the design
of FIG. 13;

FIG. 16 is a rear, left perspective view of the design of FIG.
13;
